WITNESS:

E. M. Holm,
INVENTOR
BY Victor J. Evans
ATTORNEY

UNITED STATES PATENT OFFICE.

EINER M. HOLM, OF DETROIT, MICHIGAN.

GAME.

Application filed August 15, 1925. Serial No. 50,496.

To all whom it may concern:

Be it known that I, EINER M. HOLM, a citizen of the United States, residing at Detroit, in the county of Wayne and State 5 of Michigan, have invented new and useful Improvements in Games, of which the following is a specification.

This invention relates to improvements in games and has for an object the provision of 10 a game of a novel and interesting character which may be played by two or more persons and which will afford instruction as well as amusement.

For this purpose, the invention provides 15 a game apparatus having a number of pockets of different values which are adapted to receive balls propelled over a game surface, with novel means for releasing the balls from the pockets and returning the balls to 20 the players.

With the above and other objects in view, the invention further includes the following novel features and details of construction, to be hereinafter more fully described, 25 illustrated in the accompanying drawings and pointed out in the appended claims.

In the drawings:—

Figure 1 is a plan view of a game apparatus constructed in accordance with the invention.

Figure 2 is a side view of the same.

Figure 3 is a section on the line 3—3 of Figure 1.

Figure 4 is a section on the line 4—4 of Figure 2.

Referring to the drawings in detail wherein like characters of reference denote corresponding parts, the reference character 10 indicates a playing surface which may be 10 be in the form of a board as shown, or a table. The board is supported in inclined 40 position by means of legs 11 and is provided around its edge with an upwardly extending flange 12, one end of the board and the portion of the flange extending around its end being substantially semi-circular as shown at 13.

Extending transversely across the upper surface of the board but terminating short 50 of one side edge so as to provide a passage 14, is a plurality of pockets 15 which open in the direction of the curved end of the board. These pockets are preferably provided with numbers which give each of the 55 pockets a different value, so that balls or spheres 16 may be rolled up the inclined sur-

face of the board through the passage 14 so as to engage the curved portion 13 of the flange and be deflected downward into one of the pockets 15. Two or more persons may play the game, each person rolling a predetermined number of balls with each play given a value in accordance with the number of the pockets the balls enter. The numbers are added and the player having the highest score, or the player reaching a given number first, being the winner of the game.

In order to return the balls to the players, the inner ends of the pockets 15 are closed 70 by a partition strip 16 which is mounted for vertical sliding movement through the board, this strip being common to all of the pockets and providing one wall for a compartment 17 which extends across the inner 75 end of all of the pockets. The compartment 17 is further provided with oppositely extending walls 18 at the juncture of which there is provided an outlet opening 19. This opening communicates by means of a 80 runway 20 with a receptacle 21 extending from the edge of the board.

Pivotedly mounted beneath the board as shown at 22 is a bell crank lever 23 which has one of its arms slidingly and pivotedly 85 connected to the partition strip 16 as shown at 24, while its other arm is pivotedly connected to one end of a rod 25. This rod extends through a suitable guide bracket 26 and has its opposite end pivotedly connected 90 to one arm of a bell crank lever 27, the said lever being pivotedly mounted as shown at 28 and provided with an operating button or head 29. A spring 30 is mounted upon the rod 25 and has one of its ends bearing against 95 the bracket 26 and its opposite end against a stop collar 31.

When it is desired to release the balls from the pockets 15, the button or head 29 is depressed so that the bell crank levers 100 are rocked upon their pivots to move the partition strip downward. The balls will then roll by gravity into the compartment 17 and will be directed to the outlet opening 19 by means of the inclined walls 18, the 105 balls passing along the run-way 20 into the receptacle 21. When pressure upon the button or head is released, the spring 30 will return the partition strip 16 to its normal position.

The invention is susceptible of various changes in its form, proportions and minor

details of construction and the right is herein reserved to make such changes as properly fall within the scope of the appended claims.

Having described the invention what is claimed is:—

1. A game apparatus comprising an inclined board having an upstanding marginal flange curved at one end of the board, a plurality of pockets extending transversely across the board adjacent the curved portion of the flange and opening toward said curved portion, said pockets being arranged to provide a passage between one of the pockets and the adjacent portion of the flange, a compartment extending across one end of all of the pockets, a movable partition strip dividing the pockets from the compartment, said strip being common to and providing a bottom wall for said pockets, yieldable means to hold the partition strip in place and means to move the partition strip to provide communication between the pockets and compartment.

2. A game apparatus comprising an inclined board having an upstanding marginal flange curved at one end of the board, a plurality of pockets extending transversely across the board adjacent the curved portion of the flange and opening toward said curved portion, said pockets being arranged to provide a passage between one of the pockets and the adjacent portion of the flange, a compartment extending across one end of all of the pockets, a movable partition strip dividing the pockets from the compartment, said strip being common to and providing a bottom wall for said pockets, yieldable means to hold the partition strip in place, means to move the partition strip to provide communication between the pockets and compartment and a receptacle located at one edge of the board and having communication with the compartment.

dividing the compartment from the pockets, said strip being common to and providing a bottom wall for all of the pockets, a pivotally mounted bell crank lever having a sliding pivotal connection with the partition strip, a second pivotally mounted bell crank lever spaced from the first mentioned lever and a spring actuated rod connecting said levers to yieldingly hold the partition strip in place and provide means to move the partition strip and establish communication between the pockets and compartment. 40

3. A game apparatus comprising an inclined board having an upstanding marginal flange curved at one end of the board, a 50 plurality of pockets extending transversely across the board adjacent the curved portion of the flange and opening toward said curved portion, said pockets being arranged to provide a passage between one of the 55 pockets and the adjacent portion of the flange, a compartment extending across one end of all of the pockets, a movable partition strip dividing the pockets from the compartment, said strip being common to 60 and providing a bottom wall for said pockets, yieldable means to hold the partition strip in place, means to move the partition strip to provide communication between the pockets and compartment and a receptacle 65 located at one edge of the board and having communication with the compartment.

In testimony whereof I affix my signature.

EINER M. HOLM.
